UNITED STATES PATENT OFFICE.

JOHN LEE THOMPSON, OF MEADOW, VIRGINIA.

MORTISING AND BORING MACHINE.

Application filed February 2, 1926. Serial No. 85,597.

The object of this invention is to provide means for mortising a door in order to mount a lock, and to provide in the same tool means for boring the key-hole and a hole 5 for the knob spindle.

A further object is to provide a machine which may be operated by an unskilled workman, and which will effectively and accurately do the work of several skilled artisans, so far as the mounting of locks is concerned.

A still further object is to provide, in connection with mounting and clamping means, a slidable element mounting an auger bit 15 for boring holes for the mortise, and a swingingly mounted element carrying means for rotating the two bits designed to bore the key-hole and the hole for the knob spindle.

With the foregoing and other objects in view, the invention consists in the novel construction and arrangement of elements described, illustrated and claimed, it being understood that modifications may be made 25 within the scope of the claim, without departing from the spirit of the invention.

In the drawings forming part of this application,

Figure 1 is a view of the device in elevation.

Figure 2 is a top plan view, when in operative position with reference to the frame of a door, the latter being in vertical section.

Figure 3 is a view in elevation, from the 35 opposite side of the device to that shown in Figure 1.

Figure 4 is a vertical section on line 4-4 of Figure 1.

Figure 5 is a vertical section on line 5-5 40 of Figure 1.

Figure 6 is a section on line 6-6 of Figure 1.

Figure 7 is a section on line 7-7 of Figure 4.

Figure 8 is a detail in section on line 8-8 45 of Figure 3.

Figure 9 is a detail view showing a slotted portion of gage plate 16 adapted to permit adjustable mounting.

A main frame designated 10, may be termed a box, and is provided with longitudinally extending guides or guideways, such as 11, in which a frame 12 is slidable longitudinally, this frame carrying a vertically movable crosshead such as 13, the

latter mounting devices through which the bit or auger 14 is driven.

This element 14 is the mortising bit, and will be centered with reference to the edge of the door, as illustrated in Figure 2, when 60 the machine is clamped in position. In order to provide for doors of different thicknesses, gage plates 15 and 16 may readily be applied or removed, being mounted by means of devices shown at 17. The mortise 65 18 is shown as having been cut in frame element 19 of the door, a door panel being illustrated in cross section at 20. However, the cutaway portion 18 may be assumed to represent one of the bores made by the auger 70 14. In order to provide for the vertical movement of the end member 13 carrying the auger mounting means, guides 13' are provided, and a knob or handle 22 is connected with the vertical movable element by 75 means of a threaded pin 23 passing through slot 24, a washer being shown at 25.

The drive for auger 14 includes a socket portion or chuck 27 rotatable with gear wheel 28 meshing with gear wheel 29, the 80 latter being driven by gear wheel 30 to which movement is imparted by hollow shaft 32.

Tubular shaft 32 has a square bore, and receives a square shaft 33 mounting gear wheel 34 meshing with gear wheel 35. Wheel 35 85 is enmeshed with the wheel 36, and the latter is rigid with reference to shaft 37 mounting beveled gear wheel 38, the latter being driven by large beveled gear wheel 39, operated in any suitable manner as by means 90 of a crank handle 40. Anti-friction rollers 41 bear on the surface of gear wheel 39 and are mounted in brackets 42, as shown in Figure 2.

It will be understood that the inner frame 95 12 is slidable longitudinally of the outer frame 10, or box, incident to the advance of the auger 14 into the frame member 19 of the door, and that the telescoping elements of the shaft including sections 32 and 33, 100 permit this sliding movement, while continued drive is imparted to the auger by means of the gearing just described. Between tubular shaft member 32, and vertically movable crosshead 13, I provide a 105 universal joint 32'. In the plan view of Figure 2, it will be observed that the auger is mounted in a laterally projecting portion of the frame, in order that the bit may be properly positioned with reference to the 110

edge of the door in which the mortise is to be formed.

Pivots connected with the main frame at the point 45 are arms 46 and 47 formed on a plate 48 provided with openings through which the chucks 49 and 50 mounting the transverse augers 51 and 52 extend, in the manner shown in Figure 4. These augers 51 and 52 are designed to bore the hole for the knob spindle and to bore the key-hole.

The chucks 49 and 50 carry spindles 54 and 55, rigid with reference to gear wheels 54' and 55', and the latter mesh with a central gear wheel 56 adapted to be rotated by means of an angular stem 57. This element 57 includes a flange 58, bearing on a plate 59 having overlapping relation with reference to plate 60, these elements retaining the gear wheels 54', 56 and 55' in position.

Pivoted clamping plate 48 is retained by cam levers 61, pivoted at 61' to element 61'', the cam portions bearing on the surface of plate 48. This plate last named carries three pins 62 which are slideable in sleeves

63 carried by plate 64, and chucks 49 and 50 are adjustable in segmental slots 65 and 66 in plate 64, to permit transverse bits 51 and 52 to be correctly positioned in accordance with the space between the key-hole and knob spindle, in a given lock. Adjustment is maintained by bit-mounting arms or elements 67 held by set screws 68.

Having thus described the invention, what is claimed as new is:

In a boring machine, a main frame, gearing at one end of said frame, means for driving the gearing, an element slideable longitudinally of the frame, a crosshead slideable vertically in said element, a tool and means on the cross head for mounting and rotating the tool, a tubular shaft and a universal joint connecting the shaft with said means last named, and a shaft driven by the gearing mounted in the main frame, this shaft rotating the tubular shaft and being slideable therein.

In testimony whereof I affix my signature.

JOHN LEE THOMPSON.
